UNITED STATES PATENT OFFICE.

JOSEPH N. CAMPBELL, OF LINDEN, NEW JERSEY.

PAPER-HANGING DEVICE.

1,140,112.

Specification of Letters Patent. Patented May 18, 1915.

Application filed October 26, 1914. Serial No. 868,641.

To all whom it may concern:

Be it known that I, JOSEPH N. CAMPBELL, a citizen of the United States, and a resident of Linden, in the county of Union and State of New Jersey, have invented a new and Improved Paper-Hanging Device, of which the following is a full, clear, and exact description.

This invention relates to improvements in paper hanging devices, and has for an object to provide an improved construction which may be utilized in placing the paper directly on the wall or on the ceiling from the supply roll.

Another object of the invention is to provide a device comparatively small so as to be readily operated by a workman and raised from the floor to the ceiling when placing paper on the wall, and readily moved across the ceiling when placing paper thereon, the same being formed so as to apply the paste to the paper as it is placed on the wall.

A further object of the invention is to provide a paper hanging device in which both the paper and paste are arranged on the device and moved with the device as the same is moved over a wall.

In the accompanying drawings—Figure 1 is a front view of the device with part of the strip of paper in position ready to be applied; Fig. 2 is a section through Fig. 1 on line 2—2; Fig. 3 is a similar sectional view to that shown in Fig. 2 but with the device applied to the ceiling instead of the side wall; Fig. 4 is a top plan view of the construction shown in Fig. 1; Fig. 5 is a side view of the construction shown in Fig. 4; Fig. 6 is an enlarged detailed fragmentary sectional view through the driving mechanism and one end of the paper spindle; Fig. 7 is an enlarged detailed fragmentary sectional view through a guiding roll embodying certain features of the invention; Fig. 8 is a detailed fragmentary perspective view of one end of the supply roll.

Referring to the accompanying drawings by numerals, 1 and 2 indicate end members which may be formed of any desired material, as for instance aluminum. Connected

with these end members are bracing bars 3 and 4 and a hand gripping member 5 which together with the ends form a frame in which a number of moving parts are mounted. Connected to the ends 1 and 2 by any desired means, as for instance by bolt 6 is a drum or cylindrical member 6' having a slot 7 for receiving the knife 8, which knife is provided with a pointed section 9 in the center and with inclined slanting edges 10 and 11, whereby the paper is first punctured centrally and is then slit from said central point to the opposite edges. Arranged adjacent the drum 6' is a roller 12 journaled in the ends 1 and 2, and designed to have the paper 13 passed thereover so that strip 14 may be pressed against the wall, both by the roller 12 and by the roll of paper 15 which is arranged upon the spindle 16. The roller 12 is loosely mounted in the ends 1 and 2 as well as roller 18 which guides the paper 13 to the paste roller 19. The ends of the paste receptacle 43 are provided with extensions which receive the ends of roller 17 so that the paper 13 will be guided from roller 18 over the paste roller, and from thence to roller 12. When the parts are arranged as shown in Fig. 3 roller 18 is not utilized but roller 17 still acts in its usual capacity. The paper 13 extends from the roll 15 over what may be termed a measuring roller 20 which is provided with severing means at the ends for severing the edges of the paper before the same passes to the paste roller 19. The measuring roller 20 is provided with an end member 21, preferably of metal, which is overlapped by a metal roller 22 slightly beveled as shown in Fig. 1 so as to provide a shearing action, whereby the paper on roller 20 overlapping the cutting roller 22 will be severed. The spindle 16 carries the roll 15 of paper, which spindle has at one end a suitable journal 23 of any desired description, said journal member extending into an aperture in end 2 while the opposite end is constructed as shown in detail in Figs. 6 and 8, namely, with a socket 24, fins or webs 25 and 26, and a pair of slots 27 and 28. The socket 24 is designed to receive the end of pin 29 while the notches 27

and 28 receive the lugs 30 and 31 secured to the pin 29. The shaft or pin 29 extends through a bearing member 32 which is rigidly secured to end 1 in any desired manner, and is provided at its outer end with a bearing bracket 33 for acting as a stop for spring 34 which bears against the hub of the sprocket wheel 35. The hub of the sprocket wheel 35 preferably extends to one side an appreciable distance so as to receive a set screw 36 for locking the sprocket wheel to the shaft or pin 29. When it is desired to place the spindle 16 in operative position, journal 24 is placed in position and the sprocket wheel 35 grasped and moved outwardly until the lugs 30 and 31 have been moved into socket 37, whereupon the opening or socket 24 is brought opposite pin 29 and then the sprocket 35 is released so that spring 34 will force the end of pin 29 into socket 24 and lugs 30 and 31 into notches 27 and 28.

It will be observed that the roll of paper 15 when forced over the spindle 16 will be engaged by the fins or webs 25 and 26 and locked to the spindle, whereupon the roll of paper 15 will act as a power member when moving over the wall. The rotation of the roll of paper will cause a rotation of spindle 16, pin 29, and sprocket wheel 35. The rotation of sprocket wheel 35 will drive chain 38, which chain passes over sprocket wheels 39 and 40, and also if desired over an idler 41 which may be adjusted to take up any slack in the chain. The sprocket wheel 39 is rigidly secured to shaft 42, which shaft in turn is rigidly secured to the paste cylinder 19 so that when wheel 39 is rotated the paste roller will also be rotated. The paste roller 19 may be made from any form of foraminous material, but preferably from perforated sheet metal, and is made preferably larger than the paper roll 15 so that the peripheral speed of the paste roller will be greater than the speed of the paper 13 passing over the roller. This will cause the paste to not only be applied but to be rubbed in to the paper to a certain extent. After leaving the paste cylinder or roller 19, the paper passes under guiding roller 17 and over roller 12, and is applied directly to the wall. When the device has been raised until the edge strikes the ceiling or the picture molding or other similar obstacle, the knife 8 is operated and cuts the paper at slot 7, thus leaving a section unapplied. This section or unapplied portion is sufficiently long to reach to the ceiling.

Referring again to the paste roller 19, it will be noted that the same is mounted to rotate in a casing or receptacle 43 which is open at the top but which is rotatably mounted on the shaft 42 so that the same may be turned to the position shown in Fig.

3 when the device is used on the ceiling as hereinafter fully described. Arranged below the casing 43 is the handhold 5 which is grasped when the device is used. If desired, either of the bracing members 3 or 4 may be also grasped. Arranged slightly below the handhold 5 is a shaft 44 which is journaled in the ends 1 and 2, and which has sprocket wheel 40 connected therewith so that the shaft will be rotated when chain 38 is operated. Rigidly secured to shaft 44 are the cutters 22 which co-act with the end members 21 and roller 20 for severing the edges of the paper. It will be evident that either of the cutters 22 could be removed in case only one edge was to be severed. It will also be evident that both of the cutters could be removed if neither edge of the paper was to be severed. In order that the cutters may be adjusted for cutting different widths of paper and always engaging more or less tightly the ends 21, the roller 20 is made in two sections as more clearly shown in Fig. 7 wherein parts 45 and 46 are telescopically fitted together. These parts are provided with recesses or bores for receiving the spring 47 which urges the parts of the roller in opposite directions and against the respective knives 22. Knives 22 are held on roller 20 by any desired means, as for instance a suitable set screw 48. When it is desired to adjust either of the cutters 22 set screw 48 is unscrewed and the knife moved in the direction desired along shaft 44 which will cause spring 47 to be contracted or be allowed to expand. After the adjustment has been secured set screw 48 is tightened and the device is ready for work.

In order that the knife 8 may properly operate, supporting runners 49 are rigidly secured thereto. These runners are arranged in ways 50 formed by oppositely arranged angle irons. Arranged along the rear and lower face of the knife 8 as shown in Fig. 2 is an angle iron 51 through which links 52 are pivotally mounted. The links 52 have pivotally connected therewith near the outer ends arms 53, which arms are rigidly secured to shaft 54. Shaft 54 extends through the end 1 and has rigidly secured thereto a hand operated member 55. When the hand operated member 55 is rocked shaft 54 will also be rocked and knife 8 will be moved into slot 7. When the member 55 is released knife 8 will move back automatically to the position shown in Fig. 2. In order to accomplish this result an arm or lever 56 is rigidly secured to shaft 54 and a retractile spring 57 is connected with the outer end of said arm and with end 2 so as to resiliently resist any movement of shaft 54. Rigidly secured to shaft 54 are a pair of resilient arms 58 which carry a bar 59 formed of any material, as for instance a strip of wood.

Bar 59 is arranged to be near the strip of paper 13 during the operation of the device as shown in Fig. 2 but not in contact therewith. However, when knife 8 moves forward to sever the strip of paper 13 strip 59 will engage the paper 13 and by reason of the adhesive on the paper will remain in engagement therewith after the paper has been cut so that the paper may be easily drawn upwardly and over roller 12 and from thence downwardly past the paper roll 15 when it is desired to place another strip of paper on the wall.

When it is desired to use the device on the ceiling the parts are arranged as shown in Fig. 3. From this figure it will be observed that the casing or receptacle 43 is turned so as to face the ceiling, and that the paper does not engage the roller 18. The construction is the same when using the device on the ceiling, but the paper is merely threaded through the parts in a different manner so that the guiding roller 18 will not be used.

The construction and arrangement described is intended for applying paper directly to the wall or ceiling or through some other suitable construction, but if desired the device could be used merely as a paste applying construction. It also could be used as a device for trimming the edges of the paper in addition to a paste applying device, and the paper mounted on the wall in the usual manner. In order to positively hold the receptacle 43 either in the position shown in Fig. 2 or in the position shown in Fig. 3 a bar or pin 60 is rigidly secured to one end of the receptacle 43 and projects through an arc-shaped slot 61. A winged nut 62 is applied to the pin 60 and when screwed against the end of the framework the receptacle 43 will be clamped in its adjusted position.

What I claim is—

1. In a device of the character described, a frame, a paste roller arranged in the frame, a paper supporting roller, means connecting the paper supporting roller and the paste roller whereby when said paper supporting roller is rotated the paste roller will also be rotated, means for guiding paper from said paper supporting roller past said paste roller to one face of the device so as to engage the wall on that face, and a knife arranged adjacent one end of the frame adapted to sever the paper, said paper roller being arranged so as to press against the paper as the same is applied to said wall, whereby the paper roller acts as a presser roller and also as a power member for causing the rotation of the paste roller.

2. In a device of the character described, a frame, a spindle for receiving a paper roll journaled in said frame, a rotatable paste

device, means for connecting said spindle and said paste device so that when said paper roll is rotated the paste device will also be rotated, means for guiding the paper from said roll past said paste device so as to receive adhesive therefrom, means for guiding the paper after it leaves said paste roll so that it will pass beneath said roll of paper, whereby said roll of paper will press the same against a wall, and means for severing said paper into strips as the same is fed from the device.

3. In a paper hanging device of the character described, a frame, a spindle arranged near one end of said frame, a guiding roller arranged near the opposite end of the frame, said spindle being designed to receive a roll of paper, said guiding roller and said roll of paper acting as means for pressing a strip of paper against a wall, a plurality of guiding rollers for guiding a strip of paper from said paper roll to said guiding roller, a paste applying device arranged in the path of movement of said strip of paper, a reciprocating knife arranged adjacent said guiding roller for severing the paper at that point, and means for operating said knife at any time.

4. In a paper hanging device of the character described, a frame, a spindle arranged in said frame for receiving a roll, said spindle being formed with a notched end, a spring pressed reciprocating member formed with lugs adapted to be forced into said notched end for holding said spindle in place, said reciprocating member being designed to be retracted when said spindle is being removed, said spindle being formed with means for frictionally gripping said roll of paper so that when friction is brought to bear on the roll of paper the spindle will be rotated, a rotatable paste applying device, means connecting said paste applying device and said spindle whereby when said spindle is rotated said paste applying device will also be rotated, and means for guiding paper from said roll of paper past said paste applying device.

5. In a device of the character described, a frame, a paste applying device, a paper receiving spindle, means for guiding paper from said spindle to said paste applying device, said means including a cutting device for trimming the edge of said paper, means for pressing a strip of paper from said roll of paper against a wall, said roll of paper also pressing said strip of paper against said wall, and a knife for severing said strip of paper from the roll of paper on said spindle.

6. In a paper hanging device of the character described, a spindle for receiving a roll of paper, means for guiding paper from said roll to a point of utilization, a paste ap-

plying device for applying paste to said paper as the same moves toward said point of utilization, a trimming device for trimming the edge of said paper as the same passes to said point of utilization, and means operated by said spindle for moving said trimming device.

In testimony whereof I have signed my name to this specification in the presence of two subscribing witnesses.
